CLAIM

The ornamental design for combined oven barbecue and water, seasoning and drip pan, as shown.

DESCRIPTION

FIG. 1 is a perspective view of an oven barbecue with water, seasoning and drip pan, showing my new design;

FIG. 2 is a top plan view;

FIG. 3 is a bottom plan view thereof;

FIG. 4 is a front elevational view thereof, the rear elevational view being a mirror image thereof; and

FIG. 5 is a right side elevational view thereof, the left side view being a mirror image thereof.

FIG. 1

FIG. 4

FIG. 2

FIG. 3

FIG. 5
